UNITED STATES PATENT OFFICE.

NOEL PEMBERTON-BILLING, OF LONDON, ENGLAND, ASSIGNOR OF ONE-HALF TO
WORLD RECORD LIMITED, OF LONDON, ENGLAND, A BRITISH COMPANY.

TALKING MACHINE AND ATTACHMENT THEREFOR.

Application filed August 15, 1922, Serial No. 582,018, and in Great Britain March 31, 1922.

This invention consists in improvements in or relating to talking-machines of the disc-record type and attachments therefor and relates primarily to improvements in the apparatus described and claimed in my co-pending application Serial No. 582,019.

A feature of the present invention consists in a modification of that part of the subject-matter of my co-pending application which comprises, for a gramophone in which uniform speed of the spiral groove of a disc-record in relation to the stylus-point of the recording or reproducing gramophone is desired, the combination with a driven friction-wheel adapted to track with its periphery on or approximately on the spiral of the record-surface and to traverse along a straight line fixed in space and radiating from the centre of rotation of the record, and a constant speed-governor geared to the said friction-wheel, of a unitary attachment comprising the aforesaid friction-wheel and governor and secured to the gramophone and comprising means which are operated from the record and which are employed to traverse said friction-wheel across the record-surface along the straight line aforesaid. The modification consists in the above-mentioned friction-wheel being now a driving-wheel and instead of driving the traversing means from the record they are driven from the turntable or from any part rotatable therewith or with the record but not from the record itself.

A further feature of the present invention consists in means for traversing the said friction-wheel across the record-surface along the straight line aforesaid comprising means which are operated by a rotatable disc mounted in operative connection with the rim of the record or of the turntable or of any part rotating therewith.

The invention also includes other features, such as the rotatable disc above described serving as a driver and the friction-wheel of the unitary attachment constituting a driven wheel actuated by contact with the record-surface; modifications in the formation of the edge of a disc-record and in the form of a disc comprising part of the driving mechanism for the traversing means; and of the construction of the unitary attachment. All the foregoing and other features of the invention will, however, be more clearly un-

derstood with reference to the accompanying drawings, in which—

Figure 1 is a perspective view of an attachment applicable to existing or other gramophones for controlling the speed of the record in the manner described;

Figure 2 is a view of the parts shown in Figure 1 looking from the back thereof;

Figure 3 is a section through the rod 17 and lead-screw 18 in a plane parallel with that of the wheel 22 looking from the front of Figure 1;

Figure 4 is a side elevation of a mechanism similar to that shown in Figure 1 and looking from the front of that figure, with certain modifications;

Figure 5 is a view showing the friction-disc 35 in contact with the periphery of the record.

Figure 6 is a side elevation of a still further modification of a controlling device of a similar character to that illustrated in Figure 4.

Like reference numerals indicate like parts in the several figures of the drawings.

Referring to Figures 1 and 2, the gramophone-turntable is represented at 10 and a record is shown in position at 11. 12 represents a top cover of the usual box or case enclosing, for example, the driving mechanism and horn of the apparatus and situated immediately beneath the turntable 10.

The speed control attachment according to the invention is supported on a base-plate 13 which slides in marginal guides 14 secured to the cover 12 and is locked in its operative position by means of a set-screw 15. Secured to, or extending from the base-plate 13, is a pillar or standard 16 in which is mounted, each at one of its ends, a guide-rod 17 and a screw-threaded spindle 18, the outer ends of which are connected by a bracket 19. A sleeve 20 fits slidably on the guide-rod 17 and has extending from it a frame composed of two similar and parallel side members 21 spaced apart by suitable struts where required. Between the arms 21 at their outer ends is pivotally mounted a wheel 22, fast on the spindle of which is a worm-wheel 23 rotatable with the wheel 22. In depending lugs on the frame constituted by the arms 21 are pivotally mounted the two ends of a spindle 24, one end of which is formed with a worm 25 in mesh with the worm-wheel 23.

On the spindle 24 is mounted a centrifugal governor 26 of a type commonly employed to govern the motor-speed of gramophones and like machines. That is to say

5 the governor comprises, in the present embodiment, three strip-springs each with a weight secured to its middle portion and each with one end anchored to an abutment 27 fast on or forming part of the spindle 24, and its other end secured to a sleeve 28 slidingly mounted on the spindle 24. To the sleeve 28 is secured a brake-disc 29 adapted to be engaged by the end of a pivoted brake-lever 30, the position of which is adjusted 10 by means of a set-screw 31.

Between the plate 13 and an abutment 32 extending from the pillar 16 is a spindle 33 having a worm 34 at its upper end and a friction-disc 35 near its lower end. The 20 worm 34 meshes with a worm-wheel 36 fast on the spindle 18. The parts are so adjusted that the wheel 35 is brought into engagement either with the periphery of the turntable 10, as shown in Figures 1 and 2, or with the 25 periphery of the record itself, as shown in Figure 5. In the latter case it is preferred that the periphery of the record be milled or serrated as at 37 (Figure 2).

Alternatively the tooth-like portions of the 30 edge of the record may serve as rubbing surfaces frictionally and intermittently engaging the edge of the wheel 35 to impart a succession of rotational impulses to the wheel.

35 Secured to the sleeve 20 is a lever 38, the lower end of which is hollowed in a semi-cylindrical form, the hollowed portion being screw-threaded to correspond and engage with the screw-thread of the spindle 18. The 40 lever 38 is extended on the other side beyond the rod 17 to afford a handle by which its screw-threaded extremity can be swung out of engagement with the spindle 18 and at the same time the frame 21 is swung to 45 clear the wheel 22 from the surface of the record 11. The lever 38 may have a certain degree of play in its relation to the frame 21 and its lower end may normally be held in engagement with the lead-screw 18 by 50 means of a control spring one end of which is indicated at 200. The parts, in their raised positions, are shown in full lines in Figure 2 and when the parts are thus raised the sleeve 20 can be slid along the guide-rod 17 to any desired position. When the sleeve 55 20 has been moved to the extreme end of the guide-rod 17 adjacent the pillar 16, the inner end of one of the arms 21 can be brought to rest on the end of a set-screw 39 carried in a bracket 40 secured to the pillar 16. Thus, when the device is not in use the 60 wheel 22, which is preferably furnished with a rubber tread of V-section, is raised clear of the record or turntable surface, thereby avoiding the production of a flat on the 65

tread which might otherwise be formed were it to rest on either of those surfaces during its periods of non-operation.

The pitch of the screw-threads on the 70 spindle 18 is equal to the pitch of the convolutions of the spiral groove of the record 11; and the diameter of the wheel 35 is so chosen, dependent upon the diameter of the turntable or record with which it is to engage, that, by means of the worm-gearing 75 34, 36 the spindle 18 is given one complete revolution for each complete revolution of the turntable 10. The friction-disc 35 is preferably composed of flexible rubber tapering towards its outer periphery. 80

It will be appreciated that no governor is needed for the motor which drives the turntable 10 or, if a governor is provided, it will be set to allow an angular velocity at least equal to the greatest angular velocity to be attained by the turntable during the playing of the record. As the turntable rotates the wheel 22 is placed in contact with the record-surface and at the same time the screw-threaded portion of the lever 38 meshes with the lead-screw 18 and the disc 35 is in engagement with the periphery either of the turntable or of the record. The governor 26 maintains the speed of the wheel 22 constant and the latter is moved bodily along a radius of the record through a distance equal to the pitch of the spiral groove thereon during each rotation of the record. By this means the linear speed of that part of the record-surface which is in contact with the wheel 22 is maintained constant at all times and the recording or reproducing stylus-point is maintained in the same convolution of the record-spiral as that over which the wheel 22 tracks at any particular moment and is as close to the wheel 22 as is conveniently possible. The linear speed of the record-groove in relation to the stylus-point is therefore also maintained constant throughout the entire 100 traverse of the stylus-point along the record-groove. 105

It will be obvious that the apparatus may be employed, not only for reproduction of sound from an already formed record, but also during recording of sound-impressions on a record. 115

In order to facilitate the setting of the wheel 22 on any particular portion of the record, there may be provided, as shown in Figure 3, a graduated scale 50 operatively connected to and parallel with the rod 17 and relatively fixed in relation to the lever 38. Projecting from the lever 38 is an index or pointer 51 which, in conjunction with the scale 50, serves to indicate the position of the wheel 22 in relation to the record-spiral. For setting the stylus-bar to the equivalent part of the record-spiral another flat scale, correspondingly graduated, is employed 125 130

which may be placed flat on the record-surface to radiate from the centre point thereof, so that the stylus-point can be placed on the record at a position of a scale marking corresponding to that indicated by the pointer 51.

Thus, if a single record contains several 10 selections, the commencement of each selection can be given a particular scale-number so that both the wheel 22 and the stylus-point can, with the aid of their scales, be placed in positions corresponding with the commencement of any particular one of the selections.

In Figure 4 a similar apparatus is illustrated and it is shown as a unitary structure containing a motor indicated in outline at 41. In the position illustrated at 41 the motor may be carried on the base-plate 13 or a projection therefrom and drives, by means 20 of a worm 43 on to the worm-wheel 36. In the position illustrated at 42 in Figure 6 the motor is carried on the frame comprising the arms 21 and drives, by means of a worm 44, directly on to the worm-wheel 23.

25 It will be realized that although the invention has been specifically described as comprising an attachment for an existing talking-machine, it may equally well be constructed as part of a talking-machine in the first instance.

Modifications in details of construction can obviously be made without departing from the spirit of the invention.

What I claim as my invention and desire 35 to secure by Letters Patent is:—

1. For a gramophone, means for obtaining uniform speed of the spiral of a disc-record in relation to the stylus point of the gramophone, said means comprising a unitary attachment having in combination a friction wheel adapted to track with its periphery substantially on the spiral of the record, a constant speed governor geared to said friction wheel, and traversing means which constitutes part of the attachment aforesaid, which is arranged to move the friction wheel across the record in a straight radial line and which is adapted to be operatively connected with and to be driven from a part 50 that is rotatable with the record.

2. For a gramophone, means for obtaining uniform speed of the spiral of a disc-record in relation to the stylus point of the gramophone, said means comprising a unitary attachment having in combination a friction wheel adapted to track with its periphery substantially on the spiral of the record, a constant speed governor geared thereto, and traversing means for the friction wheel to move the latter across the record in a straight radial line, one element of said traversing means being so formed as to engage with and to be driven by the rim of a part which is rotatable about the axis of the record.

3. For a gramophone, means for obtaining uniform speed of the spiral of a disc-record in relation to the stylus point of the gramophone, said means comprising a unitary attachment having in combination a friction wheel adapted to track with its periphery substantially on the spiral of the record, a constant speed governor geared thereto, and traversing means for the friction wheel to move the latter across the record in a straight radial line, one element of said traversing means comprising a rotatable disc adapted to be brought into engagement with and to be driven by the rim of a part which is rotatable about the axis of the record. 50

4. For a gramophone, means for obtaining uniform speed of the spiral of a disc-record in relation to the stylus point of the gramophone, said means comprising a unitary attachment having in combination a friction wheel adapted to track with its periphery substantially on the spiral of the record, a constant speed governor geared thereto, traversing means for the friction wheel to move the latter across the record in a straight radial line, said traversing means comprising a lead-screw, a travelling frame on which the friction wheel and the governor are mounted, and means operatively connected to said travelling frame to engage the thread of the lead-screw. 55

5. For a gramophone, means for obtaining uniform speed of the spiral of a disc-record in relation to the stylus point of the gramophone, said means comprising a unitary attachment having in combination a friction wheel adapted to track with its periphery substantially on the spiral of the record, a constant speed governor geared thereto, traversing means for the friction wheel to move the latter across the record in a straight radial line, said traversing means comprising a lead-screw, a travelling frame on which the friction wheel and the governor are mounted, means operatively connected to said frame to engage the thread on the lead-screw, and a rotatable disc operatively connected with the lead-screw and adapted to engage with and to be driven by the rim of a part which is rotatable about 110 the axis of the record. 115

6. For a gramophone, means for obtaining uniform speed of the spiral of a disc-record in relation to the stylus point of the gramophone, said means comprising a unitary attachment having in combination a friction wheel adapted to track with its periphery substantially on the spiral of the record, a constant speed governor geared thereto, and traversing means for the friction wheel to move the latter across the record in a straight radial line, one element of said traversing means comprising a disc which is so formed as to engage with and to be driven by the rim of a part which is 120 125 130

rotatable about the axis of the record and which has its marginal portion at least made of flexible material.

7. For a gramophone, means for obtaining uniform speed of the spiral of a disc record in relation to the stylus point of the gramophone, said means comprising a unitary attachment having in combination a friction wheel adapted to track with its periphery substantially on the spiral of the record, a constant speed governor geared thereto, and traversing means for the friction wheel to move the latter across the record in a straight radial line, one element 10 of said traversing means comprising a disc which is so formed as to engage with and to be driven by the rim of a part which is rotatable about the axis of the record and which is formed of flexible material.

8. For a gramophone, means for obtaining uniform speed of the spiral of a disc record in relation to the stylus point of the gramophone, said means comprising a unitary attachment having in combination a friction wheel adapted to track with its periphery substantially on the spiral of the record, a constant speed governor geared thereto, traversing means for the friction wheel to move the latter across the record in a straight radial line, said traversing means comprising a lead-screw, a travelling frame on which the friction wheel and governor are mounted, means operatively connected with said frame to engage the thread of the lead-screw and means whereby said attachment can be mounted on the gramophone in such a position that the frame is moved so that the friction wheel traverses a straight radial line across the record surface.

9. For a gramophone, means for obtaining uniform speed of the spiral of a disc record in relation to the stylus point of the gramophone, said means comprising a unitary attachment having in combination a friction wheel adapted to track with its periphery substantially on the spiral of the record, a constant speed governor geared to said friction wheel, and traversing means 45 which constitutes part of the attachment aforesaid, which is arranged to move the friction wheel across the record in a straight radial line and which is adapted to be operatively connected with and to be driven from a part that is rotatable with the record, and a motor carried on said attachment and operatively connected with the friction wheel to rotate the latter and thereby to rotate the record through the intermediary 50 of the friction wheel.

10. For a gramophone, means for obtaining uniform speed of the spiral of a disc record in relation to the stylus point of the gramophone, said means comprising a unitary attachment having in combination a

friction wheel adapted to track with its periphery substantially on the spiral of the record, a constant speed governor geared thereto, traversing means for the friction wheel to move the latter across the record in a straight radial line, said traversing means comprising a lead-screw, a travelling frame on which the friction wheel and the governor are mounted, and means operatively connected to said travelling frame to engage the thread of the lead-screw and so mounted that it is movable at will into and out of engagement with the lead-screw.

11. For a gramophone, means for obtaining uniform speed of the spiral of a disc record in relation to the stylus point of the gramophone, said means comprising a unitary attachment having in combination a friction wheel adapted to track with its periphery substantially on the spiral of the record, a constant speed governor geared thereto, traversing means for the friction wheel to move the latter across the record in a straight radial line, said traversing means comprising a lead-screw, a travelling frame on which the friction wheel and the governor are mounted, means operatively connected to said travelling frame to engage the thread of the lead-screw, and means adapted to be driven from a part which is rotatable about the axis of the record, for rotating said lead-screw.

12. For a gramophone, means for obtaining uniform speed of the spiral of a disc record in relation to the stylus point of the gramophone, said means comprising a unitary attachment having in combination a friction wheel adapted to track with its periphery substantially on the spiral of the record, a constant speed governor geared thereto, traversing means for the friction wheel to move the latter across the record in a straight radial line, said traversing means comprising a lead-screw, a travelling frame on which are mounted the friction wheel and governor aforesaid and a half nut, carried by said travelling frame and adapted to engage the thread of the lead-screw, and means, driven by a part rotatable about the axis of the record, to rotate said lead-screw.

13. For a gramophone, means for obtaining uniform speed of the spiral of a disc record in relation to the stylus point of the gramophone, said means comprising a unitary attachment having in combination a friction wheel adapted to track with its periphery substantially on the spiral of the record, a constant speed governor geared thereto, traversing means for the friction wheel to move the latter across the record in a straight radial line, said traversing means comprising a lead-screw, a travelling frame on which are mounted the friction wheel and governor aforesaid, a guide for said travelling frame, means carried on said

frame to engage the thread of the lead-screw and means, driven from a part that is rotatable about the axis of the record, for rotating said lead-screw.

- 5 14. For a gramophone, means for obtaining uniform speed of the spiral of a disc record in relation to the stylus point of the gramophone, said means comprising a unitary attachment having in combination a 30 friction wheel adapted to track with its periphery substantially on the spiral of the record, a constant speed governor geared thereto, traversing means for the friction wheel to move the latter across the record in 10 a straight radial line, said traversing means comprising a lead-screw, a travelling frame on which are mounted the friction wheel and governor aforesaid, a guide for said frame, and a rotatable disc geared to 15 said lead-screw and adapted to engage with and to be driven by the rim of a part which is rotatable about the axis of the record, the travelling frame being such that the plane of the friction wheel is transverse to the 20 axis of the lead-screw.

25 15. For a gramophone, means for obtaining uniform speed of the spiral of a disc

record in relation to the stylus point of the gramophone, said means comprising a unitary attachment having in combination a 30 supporting plate adapted to be secured to a part of the gramophone, an upright pillar on said plate, a lead-screw extending laterally from said pillar, a guide parallel with and spaced from said lead-screw, a travelling frame mounted to slide on said guide, a friction wheel and a constant speed governor geared thereto, both mounted on said frame so that the plane of the friction wheel is transverse to the axis of the lead-screw, a rotatable disc also mounted on said 35 supporting plate and having a flexible margin to engage with and to be driven by the rim of a part that is rotatable about the axis of the record, and a pivoted arm mounted on said travelling frame and bearing on it a half nut to engage the thread of the lead-screw, the said arm being so disposed that it may be moved about its pivot at will into and out from engagement with said lead-screw, substantially as described. 40

45 In testimony whereof I affix my signature.

NOEL PEMBERTON-BILLING.
